FIG. 3

FIG. 5

FIG. 4

Inventor,
Philip D. Parsons.

By *John D. Parsons*
Attorney.

UNITED STATES PATENT OFFICE

PHILIP D. PARSONS, OF SWARTHMORE, PENNSYLVANIA, ASSIGNOR TO SCOTT PAPER COMPANY, A CORPORATION OF PENNSYLVANIA

DISPENSING CABINET

Application filed November 17, 1928. Serial No. 320,021.

My invention has for its object the embodiment in a dispensing cabinet of certain features of construction which will automatically cause a stack of specially folded paper towels, and the like, to feed downward by gravity through the cabinet in a positive manner and cause a flap of the lowermost towel to fall, by gravity, in such manner as to be presented through an orifice whereby it may be readily grasped and the towel withdrawn.

More specifically considering the construction, the cabinet is of a width from front wall to rear wall considerably less than the width of the articles to be dispensed, and the lower end of the structure is provided with an obliquely downwardly extending part from the front wall or cover plate and an obliquely upwardly extending part from the rear wall, the latter providing a transverse pocket adjacent to the rear wall for receiving successively the rear edges of the towels, and the former providing at a higher elevation a transverse support for successively receiving and sustaining the forward portion of the towels.

My improvements further provide a transverse opening intermediate of the obliquely downwardly extending support and the obliquely upwardly extending pocket portion, aforesaid, for permitting a lower flap on the underside of the lowermost paper towel to fall, by gravity, whereby it is presented to be grasped, while the body of the towel of which it forms a part is sustained by the pocket and the obliquely downwardly extending forward portion.

My improvements further embody in the construction above stated, wherein the front wall and the obliquely downward and rearwardly extending supporting portion is formed as a door.

My invention also comprehends other features of construction which, together with those above enumerated, will be better understood by reference to the drawings and are more specifically recited in the claims.

Referring to the drawings: Fig. 1 is a front elevation of a cabinet embodying my invention; Fig. 2 is a vertical section through the same on line 2—2 of Fig. 1; Fig. 3 is a

transverse section through the same, taken on line 3—3 of Fig. 1; Fig. 4 is a perspective view of one of the towels; and Fig. 5 is a perspective view of a portion of the cabinet frame.

2 is a box-like structure having back, sides and top, and provided at its bottom with an oblique supporting and closure plate 3 extending forward and upward from the back and having a projecting lip 7 which is bent outward from the plane of the plate 3 and so shaped that it provides between it and the transverse hinge 4 a transversely formed opening 6 of a width approximating the entire width of the box-like structure. Moreover, this opening 6 is preferably so shaped by the projecting lip 7 of the plate 3 that an increased opening at or about the middle lower part of the cabinet is provided, whereby the flap of the lowermost paper towel may be supported by the lateral portions 7a of the lip 7, so that the flap may be readily grasped between the finger and thumb in the act of withdrawing it and the paper towel of which it forms a part, as more fully described hereinafter.

8 represents the front closure and is of shorter vertical height than the back of the box-like portion 2, and has its lower end bent obliquely rearward, as at 9, in substantial alignment with the plate 3 and terminated in a hinge portion constituting a part of the transverse hinge 4 which unites it to the aforesaid plate 3 and provides, as it were, an upward continuance of the plate 3 beyond the hinge. The side edges of the front plate 8 are inwardly flanged, as at 10, to fit within the side walls 5 of the box-like structure, and the upper edge of the front plate 8 is inwardly flanged, as at 11, to fit inside of the top plate 12 of the box-like structure, and is also provided with a suitable lock 13, whereby the cabinet may be presented from being surreptitiously opened and the contents removed.

Further considering the hinged front plate 8, it will be seen that it is formed with two vertical panels 14 made by depressing the front surface and providing thereby vertical guide strips against which the paper towels

rest during their downward travel. As the width of the panels present less friction than would be presented by the entire width of the said front plate, if the panels were omitted, it is evident that less resistance is offered to the downwardly moving gravity actuated stack of paper towels within the cabinet, and consequently, they automatically feed downwardly with positiveness and accuracy.

Owing to the obliquity of the paper towels 16 within the cabinet, the weight of the towels extends to a greater extent toward the rear or back of the cabinet than at the front, and consequently very little pressure, if any, reaches the front or door portion 8. Furthermore, the forward folded ends 15 of the paper towels rest with far lighter pressure upon the plate part 9 adjacent to the hinge 4, than occurs with the rear portions 17 of the towels as they settle down into the socket portion 3a at the juncture of the back 2a and the bottom plate 3. The result of this is that a firm pull upon the flap 18 of the lowermost towel will readily withdraw the lower end of the towel from out of the socket portion 3a and through the transverse opening 6, and immediately following the release of the said lower portion of the towel and flap, the upper portion will be easily withdrawn from its contact with the supporting part 9 of the cabinet, and without disturbing the next adjacent towel above.

I do not limit myself to the use of the cabinet with towels in which both of the flaps 15 and 18 are folded to one side of the body portion, as it is equally applicable to what is known as the Z fold towel, wherein the upper flap 15 is folded over the opposite face of the body. It is, however, more satisfactory that the flap 15 should be folded downward and rest upon the metal supporting portion 9 from which it may readily slide when pulled, rather than have its free edge in frictional contact with the paper towel immediately above. Furthermore, in the fold as shown, the body part of the lowermost towel, when being withdrawn, slides over the flap 15 of the towel next adjacent to and in no way tangles the said flap.

To enable the attendant to know when the cabinet requires refilling with towels, I provide a vertical window or aperture 19 in the front plate or cover 8 adjacent to its lower vertical face, and through which the edges of the stacked paper towels may be viewed. In this manner, it may readily be ascertained that there are only a few remaining towels in the cabinet and that a refilling of the cabinet is in order.

The cabinet is easily refilled with the towels properly positioned within it by the following manipulation: The front plate or cover 8 is unlocked and swung downward into the dotted position, Fig. 2, which leaves

the transverse hinge portion 4 as a supporting rest upon which the stack of towels is placed, and upon which they may be tilted backward into the position shown in Fig. 2 before the cover is raised. On the other hand, while the towels are positioned with the body parts horizontally, the cover plate 8 may be turned upwardly and act to lift the forward edges of the towels and tilt them upon the transverse hinge into the position shown in Fig. 2 by the mere act of closing said cover plate. This oblique arrangement of the towels within the cabinet is positively assured by reason of the shape of the several parts of the cabinet, and more particularly, by having the depth of the cabinet from front to rear considerably less than the transverse width of the towels, taken across the flaps 15 and 18.

Referring more particularly to the general structure of the cabinet, I prefer to make the top and two sides in one piece of stamped sheet metal, as shown in Fig. 5, wherein the sides 5, 5, are integrally formed with the top portion 12 and the edges of said parts 5, 12, 5, flanged as at 20 for attachment to the back plate 2a by spot welding. I also provide the side portions 5 with inwardly extending panel portions 21, the said portions acting as guides for the ends of the paper towels, as indicated in dotted lines in Fig. 3. I also provide the bottom parts of the sides 5 with short flanges 22 to which the bottom plate 3 is secured by spot welding.

Furthermore, the top portion 12 of the cabinet is extended downward at the front to form a box-like structure 12a beneath which the top flange 11 of the hinged cover plate 8 is received and engaged by a spring catch 23, the spring 24 of which extends rearwardly and is spot welded to the top plate. The lock 13 is provided with a part 13a by which the spring catch 23 may be raised for releasing the hinged cover plate, when it is desired to open the cabinet for re-charging it. The flanged portion 12a of the top plate may be reinforced with an angle plate 25 which extends obliquely downward and backward to the back plate 2a where it is spot welded. This oblique plate facilitates the positioning of the paper towels when they are moved backward into position within the cabinet, the plate acting upon the rear parts of the stack of towels to depress the said ends to cause the lowermost towels to fit into the socket portion 3a at the extreme bottom and back of the cabinet.

For convenient suspension to the wall, the back plate 2a of the cabinet is provided with a middle suspension aperture 27 depressed on the inside to prevent the head of the suspension screw contacting with the paper towels as they descend. In addition to the middle suspension aperture, I provide a plurality of horizontal depressed apertures 28

through which additional screws may be passed to firmly hold the cabinet against displacement. In this manner, the cabinet is self-supporting from the screw in the middle aperture and thereafter the additional attaching screws may be applied.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details as the same are susceptible of modification in various particulars, without departing from the spirit or scope of the invention.

Having now described my invention, what I claim and desire to secure by Letters Patent is:

1. In a cabinet for dispensing paper towels and the like, a box body portion open at the front and having at the bottom an oblique closure portion forming a transverse socket between it and the back of the box body portion and providing a forward lip at a slightly higher elevation than the socket portion and over which the article to be dispensed may be withdrawn, combined with a cover plate at the front of the box to close it, said cover plate having an inclined rearwardly extending flange at its lower part, said flange transversely hinged to the box body portion at a distance above the lip and intermediate of the front cover plate and the back of the box to provide a transverse opening between said cover plate and the forwardly projecting lip, and in which further, the rearwardly extending flange of the cover plate is inclined in alinement with the transverse socket portion to provide an inwardly and downwardly directed support for the forward portions of the articles to be dispensed, and wherein further, the lip of the bottom closure portion forming the lower boundary of the delivery opening is bent downward in the middle to increase the size of the opening in a vertical direction at or adjacent to its middle portion.

2. In a cabinet for dispensing paper towels and the like, a box body portion open at the front and having at the bottom an oblique closure portion forming a socket between it and the back of the box body portion and providing above and forward of the socket a transverse delivery aperture of approximately the full width of the cabinet, combined with a front cover plate having an angular portion at the bottom extending rearwardly and hinged in advance of the transverse delivery opening forward of the bottom closure portion and at a distance to the rear of the front of the cover plate, and wherein further, the upper interior portion

of the box body is provided with an obliquely and rearwardly extending guide plate for insuring the depression of the rear ends of the articles being inserted, whereby said articles incline downwardly.

In testimony of which invention, I hereunto set my hand.

PHILIP D. PARSONS.
